TRAFFIC INTERSECTION

Arturo Olivero Cedeno, Ocampo 1073, Monterrey,
Mexico

Filed Oct. 21, 1957, Ser. No. 691,375

6 Claims. (Cl. 94—1)

This invention relates to traffic intersections and more particularly to a traffic circle for handling traffic between a plurality of streets.

In traffic circles heretofore used it is necessary to turn onto and turn off of the traffic circle at the outboard lane. Thus, while interior lanes are provided, their usefulness is greatly restricted and when they are used it is necessary for vehicles to be constantly shifting lanes while at the same time watching traffic entering the circle. As entering traffic must merge with traffic in the outboard lane, it is difficult to get onto a crowded traffic circle.

By this invention there is provided a traffic circle in which the problem of incoming merging traffic is eliminated, inside lanes are used, and traffic can leave the circle from an inside lane.

It is an object of this invention to provide a traffic circle in which cars may enter the circle without merging with other traffic.

Another object is to provide a traffic circle in which cars do not shift between the several lanes of the circle.

Another object is to provide a traffic circle in which cars may leave the circle from an interior lane without first emerging with traffic in an exterior lane.

Another object is to provide a traffic circle in which a car may enter the circle from any given street and exit onto any other given street without merging with other traffic or changing lanes while in the circle.

Another object is to provide a traffic circle as in the preceding object for serving at least four streets in which traffic is conveyed about the circle by a plurality of side-by-side winding lanes and the number of winding lanes at any one point is three less than the number of streets serviced by the circle.

Another object is to provide a multi-level traffic circle in which automobile traffic is handled between all streets without merging traffic or shifting lanes and in which over-height vehicles, such as trucks, are handled separately to avoid the expense of spacing the levels a sufficient distance to accommodate over-height vehicles.

Other objects, features and advantages of this invention will be apparent from the drawings, the specification and the claims.

In the drawings wherein there are shown by way of illustration several embodiments of this invention and wherein like numerals indicate like parts:

Figure 1 is a plan view of a traffic circle constructed in accordance with this invention and with a section of the upper level broken away to illustrate details of the lower level—the streets of the intersection being numbered successively 1 through 8 and outgoing lanes of each street being numbered to indicate the origin of its traffic;

Figure 2 is a schematic view of a slightly modified form of intersection; and

Figure 3 is a schematic view of a further modified form of intersection.

2

The Figure 1 form of intersection of this invention is characterized by a plurality of side-by-side winding lanes 10 through 17. One lane is provided for each street serviced by the intersection and, therefore, their number 5 will increase or decrease with the number of streets serviced by the intersection. The lanes 10 through 17 receive incoming traffic from streets 1 through 8, respectively, and convey it in a coiling or spiraling path toward the center of the intersection. In other words, each 10 of the lanes 10 through 17 coil toward the center of the intersection. The intersection is so constructed that traffic does not switch between these lanes, and permanent barriers may be erected between these lanes to prevent crossing of lanes.

15 The winding lanes 10 through 17 are provided at a common level and traffic leaves these lanes by moving to another level after which it exits to the streets again without crossing lanes and in the preferred form without merging traffic. Thus, it will be seen that the intersection 20 is provided with an upper level indicated generally at 18 and a lower level indicated generally at 19. In the form of intersection illustrated the winding lanes are in the upper level.

Traffic leaves the winding lanes of the upper level 25 through a series of ramps leading to the lower level. One ramp is provided for each winding lane at circumferentially spaced points about the intersection. These points correspond in number to the number of streets serviced by the intersection. Thus, the group of ramps 30 indicated generally at 21, which may be designated 21a through 21e, provide for transferring traffic from each winding lane 10, and 13 through 17 to the lower level. In like manner the group of ramps indicated generally at 22 and comprising ramps 22a through 22e provide for 35 transfer of traffic to the lower level just before reaching street No. 3. In like manner groups of ramps are provided about the circle for transferring traffic from the winding lanes of the upper level to each of the streets serviced by the intersection. These groups of ramps 40 are shown at 23 through 28, and the individual ramps of each group are numbered in the same manner as explained in the discussion of groups 21 and 22.

Means for connecting the traffic from each ramp at the 45 lower level with the streets is provided. Preferably these lanes are sufficient in number to avoid merging traffic. Referring to the lanes of the lower level servicing street No. 5, it will be noted that separate lanes 29 through 35 are provided. These lanes may be considered as part of or as a continuation of ramps 23 through 28, and in the 50 claims they are so considered. By tracing traffic in the lower level, it will be noted that lane 29 conveys traffic from ramp 24e to a point outboard of the winding lanes and then proceeds with the winding lanes to a point adjacent street 6 where it turns under the incoming winding lane 15 and feeds traffic onto the lane numbered 8 of street 6. By handling one lane of traffic in this manner, the winding lanes which are at an upper level may be reduced in length. If it is not desired to handle this traffic in this manner, the winding lane 17 may be extended to 55 a point opposite the termination of winding lane 10 and discharge its traffic on the opposite side of street 6, that is lane 8 of street 6 would be moved to the right-hand side of street 6 and would be adjacent the curb of street 6 in leaving the traffic circle. Traffic from winding lane 17 wishing to turn onto street 5 proceeds along lower level 60 lane 30. In like manner, traffic from winding lanes 10, 11, 12 and 13 proceeds along lanes 31, 32, 33 and 34 to the outbound lanes of street 5.

The traffic circle is symmetrical, and the handling of traffic in the exposed portion of the lower level is repeated in exactly the same manner eight times about the circle.

The illustrated form of circle as thus far explained han-

dles traffic between any street and six of the other seven streets proceeding in a clockwise manner. Right turn traffic to the adjacent counterclockwise street is handled in a different manner. However, it will be understood that if desired, the winding lanes could be continued another step to handle traffic between all of the streets serviced by the intersection.

It is preferred to construct the two levels of the traffic circle with a clearance which will permit passenger cars only and to handle over-height vehicles, such as trucks, in a different manner. For this purpose the traffic circle may be surrounded by a bridge 36 which functions in the manner of the usual traffic circle to handle over-height vehicles. Access ramps such as indicated at 37, street 5, provide for access and exit from the surrounding bridge 36. This bridge also provides for right turn traffic between adjacent streets. While there will be some merging of traffic as right turn traffic moves onto bridge 36, it will be minor and unobjectionable. Right turn traffic will leave the bridge in a special lane such as shown at 38, street 4, and no difficulty will be experienced in leaving the bridge. While the entry and exit ramps for each street may be separated, it is preferred that they be side-by-side to minimize cost of the ramps leading to and from the bridge.

The handling of traffic entering from street 5 is shown by lines of V's and it will be traced here to fully explain the way in which traffic flows on the circle. Traffic for each of the other streets is handled in the identical manner. A motorist desiring to turn from street 5 to street 4 goes up ramp 37 and proceeds to the right as indicated by the arrows and leaves in lane 38 of street 4. A motorist desiring to turn onto any of the other streets proceeds in the two outboard lanes numbered 5 onto winding lane 14. If it is desired to turn onto street 6, the ramp 25a is entered to drop to the lower level. From the lower level a lane 34 is provided which connects with the outgoing lane numbered 5 of street 6. If it is desired to leave the circle at street 7, the motorist continues along winding lane 14 to ramp 26b. A lane 33 connects ramp 26b with the outgoing lane 5 of street 7. If desired, the motorist may bypass ramp 26b and proceed to ramp 27c which leads to street 8. Ramp 27 is connected by a lane 32 with lane numbered 5 of street 8. If desired, ramp 27c may be bypassed and the motorist may proceed to ramp 28d. By dropping down ramp 28d and proceeding along lane 31, the motorist may leave the circle and exit on lane 5 of street 1. Ramp 28d may be bypassed and the motorist may proceed along winding lane 14 to ramp 21e. From ramp 21e the motorist may enter lane 30 to proceed to lane 5 of street 2, or he may enter lane 29 and proceed to lane 5 of street 3. In addition to the directional V's, there is also shown a number of automobiles traveling like paths beginning at lane 6. The automobiles shown in solid outline are in the upper level of the circle and those shown in dashed outline are in the lower level of the intersection.

Referring to Figure 2, there is shown a slightly modified form of circle. In this case, each of the winding lanes extends a sufficient distance to feed directly to the outgoing street from all down ramps, thus eliminating the lane 29 in the other intersection which proceeds along the outboard portion of the winding lanes to the next clockwise lane. Thus, taking lane 40 by way of example, it will be noted that traffic enters this lane from street 41 by passing under the outer bridge 42 and then on to the upper level which is represented by solid lanes. Proceeding along lane 40 it will be noted that traffic may drop to the lower level along ramp 43 to reach street 44. In like manner traffic may drop on ramp 45 to reach street 46, ramp 47 to reach street 48, ramp 49 to reach street 50, ramp 51 to reach street 52, and ramp 53 to reach street 54. It will be noted that the ramps proceed to the lower level and traffic from the three outboard ramps of each group merge into a single line of outgoing traffic while traffic from the three inboard ramps of each group merges

into a second single line of outgoing traffic. Truck and right turn traffic to adjacent streets are handled on bridge 42 in the same manner as explained in connection with Figure 1.

The form of invention shown in Figure 2 provides for merging of traffic while leaving the circle, thus reducing traffic to five lanes immediately upon reaching the street. Merging turning traffic is undesirable, and the Figure 1 form of invention which has a large number of outgoing lanes is preferred. Of course, the seven outgoing lanes may be merged into three outgoing lanes immediately after leaving the circle, preferably in a progressive manner to reduce to six lane traffic on each street.

Referring now to Figure 3, there is shown a traffic circle constructed in accordance with this invention which follows generally the Figure 1 embodiment except that there are four streets serviced by the circle and the upper level of the Figure 1 intersection is replaced by four individual bridges 55, 56, 57 and 58.

Each section of the intersection is identical and, therefore, traffic movement from only one street will be traced.

Considering traffic flowing into the traffic circle from street 59, provision is made for right turn traffic by the U-shaped lane 61 which receives traffic from the curb lane of street 59 and discharges such traffic onto street 62.

Traffic desiring to exit on either streets 63 or 64 proceeds on inbound lane 65 of street 59 to the traffic circle. As lane 65 reaches the circle, it is conveyed across the other traffic of the circle at this point at a different elevation, such as by bridge 55.

From bridge 55 incoming traffic proceeds along lane 66 of the traffic circle. This lane extends less than 360 degrees, in the case of a symmetrical intersection approximately 180 degrees, to street 64.

As lane 66 of the traffic circle reaches the next adjacent street 63, it crosses the incoming traffic from street 63 at a different level as by bridge 56 which conveys the incoming traffic from street 63 over lane 66. After passing through bridge 56, the traffic in lane 66 may divide and turn left into lane 67 to proceed outboard on street 63 or may proceed to the right on a continuation of lane 66 to street 64.

As traffic in lane 66 reaches street 64, it again crosses the incoming traffic at a different level as by bridge 57 and empties onto street 64 in lane 68.

From the above it will be seen that there has been provided a very simple four-street intersection in which there is no merging traffic and in which only four bridges are needed to convey traffic to and from each intersection without merging traffic.

The foregoing disclosure and description of the invention is illustrative and explanatory thereof and various changes may be made within the scope of the appended claims without departing from the spirit of the invention.

I claim:

1. A traffic interchange comprising, a traffic circle and a plurality of streets radiating therefrom, said traffic circle comprising, a plurality of spiraling side-by-side lanes on one level, each of said lanes beginning at the outboard of said circle at progressively spaced points, ramps interconnecting each of said streets with the outboard end of a corresponding spiraling lane, and ramps connecting spaced points on each of said spiraling lanes with said radiating streets, each of said last mentioned ramps crossing the contiguous spiraling lanes outboard of said spaced points at an elevation different from the elevation of the spiraling lanes.

2. A traffic interchange comprising, a traffic circle and a plurality of streets radiating therefrom, said traffic circle comprising, a plurality of spiraling side-by-side lanes on one level, each of said lanes beginning at the outboard of said circle at progressively spaced points in the vicinity of said radiating streets, entrance ramps interconnecting each of said streets with the outboard

end of a corresponding spiraling lane, and exit ramps departing from spaced points on each of said spiraling lanes and connecting each of said spiraling lanes with a plurality of said radiating streets, each of said exit ramps crossing the contiguous spiraling lanes outboard of said spaced points at an elevation different from the elevation of the spiraling lanes.

3. A traffic interchange comprising, a traffic circle and a plurality of streets radiating therefrom, said traffic circle comprising, a plurality of spiraling side-by-side lanes on an upper level, each of said lanes beginning at the outboard of said circle at progressively spaced points in the vicinity of said radiating streets, entrance ramps interconnecting each of said streets with the outboard end of a corresponding elevated lane, and downwardly extending exit lanes departing from spaced points on each of said spiraling lanes and connecting each of said spiraling lanes with a plurality of said radiating streets, each of said downwardly extending ramps passing under the contiguous elevated lanes outboard of 20 said spaced points.

4. The traffic interchange of claim 3 wherein all of the exit ramps leading from the spiraling lanes at one angular position about the circle with the exception of the exit ramp servicing the inboard spiraling lane leading to one street, said ramp servicing the inboard spiraling lane extending to the exterior of the circle and thence about the circle to the next adjacent street.

5. The traffic interchange of claim 3 wherein the spiraling lanes spiral toward the center in one circular direction and a lane extends in the opposite direction

about the circle between first and second adjacent streets to provide for traffic flow from said first to said second streets.

6. The traffic interchange of claim 3 wherein an elevated bridge is provided which surrounds the traffic circle and access and exit ramps are provided between each street and the bridge, said bridge handling over-height vehicles and turn traffic in one direction between adjacent streets.
